UNITED STATES PATENT OFFICE.

CHARLES P. EISENHAUER, OF DAYTON, OHIO, ASSIGNOR TO THE DURO PUMP AND MANUFACTURING COMPANY, OF DAYTON, OHIO, A CORPORATION OF OHIO.

DEEP-WELL PUMP.

Application filed October 20, 1923. Serial No. 669,710.

To all whom it may concern:

Be it known that I, CHARLES P. EISENHAUER, a citizen of the United States, residing at Dayton, in the county of Montgomery and State of Ohio, have invented certain new and useful Improvements in Deep-Well Pumps, of which the following is a specification.

My invention relates to pumps and more particularly to deep well pumps of the double acting and double displacement type.

In the present construction, there is contemplated a pump mechanism to be suspended at a low level within a well wherein the water does not rise sufficiently high to be drawn by the usual suction pump. The construction involves a pump cylinder connected to the lower end of the pump stock or well tube, within which cylinder reciprocates a single plunger or piston. The cylinder is provided with a valved water inlet orifice at its lower end below the plunger or piston and is also provided with a second valved water inlet orifice in the wall of the pump cylinder above the plunger or piston.

On the up-stroke the piston draws water through the valved inlet in the lower end of the cylinder and upon the downstroke it draws a charge of water through the lateral port in the cylinder wall above the piston. These respective charges of water are displaced by the piston upon reversal of its direction of movement. Each charge of water is forced by the displacement movement of the pump piston through an outlet from the respective compartments above and below the piston head into the water column or discharge pipe common to both of the displacement chambers. The outlets from the respective chambers are controlled by independent check valves.

The outlet passage from the lower displacement chamber or that beneath the piston head or plunger to the common discharge pipe or water column is through the hollow stem of the piston or plunger and the corresponding check valve may be located either in the piston head or adjacent to the upper end of the cylinder or at the point of communication between the hollow piston rod and the common discharge pipe. The construction is shown embodied in both an open type and a closed type of pump cylinder mechanism. That is to say, in the open type the parts are so constructed that the valve mounting

and valves carried thereby are of smaller diameter than the inside of the column or discharge pipe which permits all the valves to be withdrawn from the well by means of the plunger rod when repairs are required, without disturbing the water column or discharge pipe. To the contrary the closed type of construction does not permit the withdrawal of the valve mounting but necessitates the removal of the entire discharge pipe of water column and cylinder to afford access to the valve. In the open type construction, the invention involves improved means for seating and unseating the valve mountings which may be successfully operated by manipulation of the pump rod.

The object of the invention is to simplify the structure as well as the means and mode of operation of such deep well pumps whereby they will not only be cheapened in construction, but will be more efficient in use, positive in operation, uniform in action, of increased durability and unlikely to get out of repair.

A further object of the invention is to provide a pump having substantially double capacity of the usual single acting cylinder of the same displacement when operated at similar speeds.

A further object of the invention is to provide such double acting deep well pump which will deliver a continuous discharge of substantially uniform volume on both the up and the down strokes.

A further object of the invention is to provide a pump wherein the operation is a balanced one requiring substantially the same power to depress the piston, that is required to elevate the piston, thereby adapting the pump for power actuation. By providing such balanced construction wherein the resistance to the movement of the piston upon the up and down stroke is substantially equalized the intermittent power requirement and consequent jerking operation of the usual pump mechanism is eliminated.

Moreover, the present construction is so arranged that the weight of the piston and pump rod is compensated for by a slight variation of the water charges on the up and down strokes.

A further object of the invention is to provide such a construction which will be compact but easily accessible and to afford improved means for disengaging the mech-

anism within the cylinder or removal and for reseating such pump parts by the manipulation of the pump rod without the necessity of withdrawing the discharge pipe or water column from the well.

With the above primary and other incidental objects in view as will more fully appear in the specification, the invention consists of the features of construction, the parts and combinations thereof, and the mode of operation, or their equivalents as hereinafter described and set forth in the claims.

In the accompanying drawings wherein is shown the preferred but obviously not necessarily the only forms of the embodiment of the invention, Fig. 1 is a longitudinal sectional view of the deep well pump mechanism forming the subject matter hereof embodied in an open type of construction wherein the parts are removable through the discharge pipe or water column by manipulation of the pump rod. Fig. 2 is a similar longitudinal sectional view of the pump cylinder showing the parts assembled in a closed type of construction involving such modifications of the mechanism particularly the location of the outlet check valve from the lower displacement chamber, which variation obviously can be embodied in the open type of construction illustrated in Fig. 1.

Like parts are indicated by similar characters of reference throughout the different views.

Referring to the drawings, 1 is the water column or discharge pipe suspended in the well to the lower end of which is connected by means of an intermediate coupling section 2, the brass pump cylinder 3. Mounted for reciprocation within the cylinder 3 is a hollow plunger head or piston 4 provided with cup leather packing rings 5 and from which extends upwardly the hollow plunger stem or piston rod 6. At its upper end this hollow piston rod or stem 6 is interconnected by an open sided or cage like coupling 7 with the reciprocating pump rod 8. The rod 8 is connected at its upper end to any suitable actuating mechanism by which the rod and plunger or piston may be reciprocated within the cylinder 3. It will be understood that the cylinder 3 is ordinarily constructed of much greater length than is indicated in the drawings wherein the cylinder is shown broken away. Thus the plunger or piston head 4 is enabled to reciprocate throughout a stroke of considerable length.

At the lower end the cylinder 3 is provided with a fitting 9 which forms the intake for the cylinder upon the up-stroke of the piston. A valve seat 10 engages a tapered bore within the fitting 9 and receives an inlet check valve 11 seating thereon and enclosed within a valve cage 12 surrounding the valve 11 and having screw

threaded connection with the valve seat 10. The valve seat 10 and fitting 9 being correspondingly tapered, the seat is secured by being driven tightly within the tapered bore of the fitting 9. To effect such driving engagement the piston or plunger head 4 is provided with a dependent stud 13 projecting from a spider or cross bar 14 in the open end of the plunger head which stud carries a transverse pin 15 adapted to engage the upper edge of the valve cage 12 when the piston head and pump rod are depressed to an abnormal extent. The normal range of movement of the piston head or plunger 4 is such that the pin 15 will not contact the valve cage 12. However, upon disconnecting the upper end of the pump rod 8 the rod may be lowered to cause the transverse pin 15 to impinge upon the upper end of the cage 12 and by repeated blows drive the valve cage into tight engagement in the fitting 9. To disengage the valve seat 10, the cage 12 is provided with bayonet slots 16 into which the ends of the pin 15 may be lowered by giving to the pump rod a partial rotation. By lowering the pump rod to pass the projecting ends of the pin 15 into the bayonet slots 16 and giving to the rod a partial rotation to effect their interengagement with the cage 12, the valve seat 10 with the valve 11 and cage 12 may be withdrawn as a single unit.

During normal operation, the lower limit of the range of movement of the piston head is such that there will be no interference nor engagement between the transverse pin 15 and the valve cage. Obviously, as the piston head or plunger 4 is drawn upward, a charge of water will be drawn through the inlet orifice in the fitting 9 and past the inlet check valve 12 into the lower displacement chamber 17 beneath the plunger head. Upon the reversal of the stroke of the plunger head 4, that is during its down stroke the water drawn into the chamber 17 will be displaced by the piston head 4 upwardly through the interior of the head 4 and then the hollow stem or piston rod 6 and will be discharged past the check valve 18 in the hollow open sided coupling 7 at the upper end of the stem 6 and then into the water column or discharge pipe 1 leading upwardly to the discharge pump or other water outlet from the well.

Located in the intermediate coupling section 2 between the discharge pipe 1 and cylinder 3 is a second valve cage or mounting supporting two independent check valves to wit, an annular inlet check valve 20 and a second discharge check valve 21. The valve cage or mounting 19 is further provided with a packing gland 22 surrounding the hollow piston stem or rod 6 and through which such stem reciprocates. This packing gland 22 has been shown provided with the

usual or ordinary form dunce cap packing. However, other forms of packing obviously may be substituted. The coupling section 2 is provided with a plurality of laterally disposed inlet orifices 23 exteriorly surrounded by a screen jacket 24. The inlet orifices 23 are controlled by the annular check valve 20. It is to be noted that the check valve 20 has an internal diameter somewhat greater than the external diameter of the stem or piston rod 6, and the valve seat 25 is similarly proportioned to afford a water passage 26 through which water entering through the inlet port 23 past the check valve 20 may be passed downwardly into the upper displacement chamber 27 located above the plunger head 4 and intermediate the head 4 and the valve mounting or cage 19.

Upon the down stroke of the plunger by which the charge of water is displaced from the chamber 17, a second charge of water is drawn into the upper chamber 27 through the inlet port 23 and past the valve 20 and through the passage 26. Thus the upper displacement chamber is being filled while the lower chamber is being emptied. Upon the reverse stroke or upward movement of the piston head 4 by which the charge of water is drawn into the lower displacement chamber 17, the charge of water already in the upper chamber 27 is displaced by the rise of the piston or plunger such body of water passing upwardly through the passage 26 and the interior of the annular valve 20 thence through the annular passage 28 in the mounting or cage 19 and past the discharge check valve 21 into the water column or discharge pipe 1 in which this charge intermingles with that discharged from the lower chamber 17 through the hollow stem 6 and past the check valve 18. The capacity of the upper and lower displacement chambers 27 and 17 is approximately the same except for the volume in the upper chamber displaced by the hollow stem or rod 6. This slight difference of water capacity tends to compensate for the weight of the pump rod and plunger head. Thus on the down stroke when gravity due to the weight of the pump rod or plunger supplements the power applied to the pump apparatus to expel the water from the chamber 17 approximately the same power effort is required to depress the plunger as is required upon the return stroke to lift the body of water within the chamber 27 against the pressure within the discharge pipe 1 with the added weight or gravity influence of the pump rod and plunger. Thus the resistance or the power requirement necessary to overcome the resistance is equalized in the opposite direction of movement of the plunger.

The cage 19 or mounting for the valves 20 and 21 has a tapered seating engagement in the coupling section 2 from which it may

be dislodged for removal from the well by the upward impact of the head 4 upon the lower end of such mounting or cage when the pump rod is raised to an abnormal height. Normally the plunger head 4 does not engage the mounting or cage 19 at the upper limit of its stroke. However, upon disconnection of the upper end of the pump rod and its elevation to an extreme height the mounting or cage 19 may be dislodged and lifted from the cylinder and through the discharge pipe 1 by the withdrawal of the pump rod and plunger. Upon the return of these parts to the well, the lower end of the coupling 7 may be made to impinge upon the head 29 of the valve mounting 19 to drive this mounting or cage 19 into engagement with its tapered seat in the coupling member 2. In its normal range of operation the coupling 7 does not descend at the lower limit of its travel into engagement with the head 29 of the mounting 19 but by turning the pump rod as before described into such position that the transverse pin 15 will enter within the bayonet slot 16 of the lowermost valve cage 12, the pump rod is permitted sufficient play to enable the driving engagement of the coupling 7 and head 29.

The closed type of construction illustrated in Fig. 2 is substantially identical with that shown in Fig. 1 except the valve mountings or cages and seats are so interconnected in the structure that they cannot be removed without withdrawing the discharge pipe or water column and disassembling the structure. As a modification, there is shown in Fig. 2 a transposition of the outlet check valve from the lower chamber 17.

Obviously the pump cylinder as shown in Fig. 1 must be submerged in order that it may operate as a double action pump. There are installations, however, where the pump cylinder is set some distance above the water level and a suction pipe extending below the water level is connected to the lower end of the cylinder. In order that the intake ports to the upper chamber may function under such circumstances, a jacket 30 is shown in Fig. 2 surrounding the cylinder and forming an annular water space with which the valved inlet ports at the upper end of the cylinder communicate. The annular space communicates at its lower end with the suction or supply pipe through a series of ports 31. Such water space thus becomes in effect a continuation of the suction pipe supplying the intake valve at the top of the cylinder. The jacket is intended for application also to the construction shown in Fig. 1.

From the above description it will be apparent that there is thus provided a device of the character described possessing the particular features of advantage before enumerated as desirable, but which obviously is

susceptible of modification in its form, proportions, detail construction and arrangement of parts without departing from the principle involved or sacrificing any of its advantages.

While in order to comply with the statute, the invention has been described in language more or less specific as to structural features, it is to be understood that the invention is not limited to the specific details shown, but that the means and construction herein disclosed comprises the preferred form of several modes of putting the invention into effect and the invention is, therefore, claimed in any of its forms or modifications within the legitimate and valid scope of the appended claims.

Having thus described my invention, I claim:

- 20 1. The combination with a double acting pump cylinder, of upper and lower inlet valve seats removably engaged in the cylinder and adapted to be upwardly displaced, a plunger piston operating within the cylinder between the valve seats, both valve seats being engageable with the plunger piston for elevation out of the cylinder by abnormal movement of the plunger, said plunger being engageable with each of the valve 25 seats independent of the other for driving said valve seats into engagement with the cylinder.
- 30 2. The combination with a pump cylinder and upwardly displaceable upper and lower valve seats removably mounted in the cylinder, of a plunger piston operating within the cylinder intermediate the upper and lower displaceable valve seats, and engageable with both valve seats for lifting them 35 from and reengaging them in the cylinder, said plunger piston impinging upon abnormal down stroke upon one of said valve seats when in one position of revolute adjustment, and when in a different position 40 of revolute adjustment impinging upon the other of the valve seats to drive said valve seats into engagement with the cylinder.
- 45 3. The combination with a pump cylinder and upwardly displaceable upper and lower valve seats removably mounted in the cylinder, of a plunger piston operating within the cylinder intermediate the upper and lower displaceable valve seats, and engage-

able with both valve seats for lifting them 55 from and reengaging them in the cylinder, and means carried by the plunger piston for imparting driving blows to each of the valve seats independently for engaging the valve seats in the cylinder.

4. The combination with a pump cylinder and upwardly displaceable upper and lower valve seats removably mounted in the cylinder, of a plunger piston operating within the cylinder intermediate the upper and 60 lower displaceable valve seats, and engageable with both valve seats for lifting them from and reengaging them in the cylinder, said plunger piston being engageable with first one and then the other of said valve 65 seats upon partial rotation of the plunger piston.

5. The combination with a pump cylinder and upwardly displaceable upper and lower valve seats removably mounted in the cylinder, of a plunger piston operating within the cylinder intermediate the upper and lower displaceable valve seats and engageable with both valve seats for lifting them 70 from and reengaging them in the cylinder, and means for effecting such replacement engagement of the valve seats singly.

6. The combination with a pump cylinder and upwardly displaceable upper and lower valve seats removably mounted in the cylinder, of a plunger piston operating within the cylinder intermediate the upper and lower valve seats, and means for operatively 75 engaging the piston plunger with either of the valve seats independent of the other so upon abnormally extended down stroke of the plunger piston.

7. The combination with a pump cylinder and upwardly displaceable upper and lower valve seats removably mounted in the cylinder, of a plunger piston operating within the cylinder intermediate the upper and lower valve seats and means for operatively engaging the piston plunger with either of the valve seats independent of the other, 80 such engagement being controlled by partial rotation of the plunger piston.

In testimony whereof, I have hereunto set my hand this 5th day of October A. D. 1923.

CHARLES P. EISENHAUER.
